COLLAPSIBLE PAPERBOARD LIQUID DISPENSING CONTAINER

Duryea Bensel, New York, N. Y., assignor to
Bensel Corporation, New York, N. Y., a corpora-
tion of Delaware

Application June 5, 1937, Serial No. 146,536

9 Claims. (Cl. 229—41)

The present invention relates to an improvement in paper board cartons for containing, shipping and dispensing fluids.

The important feature herein is the provision of means on the carton, which, in the present instance, is of a rectangular formation, whereby the carton, in dispensing the liquid contents therefrom, may be completely collapsed, manually, thereby to enable the dispenser to completely 10 extrude the contents therefrom, quickly, by hand or by mechanical pressure.

This latter feature is quite essential when the liquid contents of the container is lubricating oil, such as is used in automobile engines and 15 the like, wherein such oil is heavy and viscous, and flows out very slowly. By the collapsing of the carton, the discharge of the residual oil from the container may be hastened by squeezing opposite sides of the container together, to be explained 20 more in detail later.

A further advantage lies in the provision of a flexible, puncturable, liner of liquid and leak 25 proof nature, for lining the interior of the container, and for containing the liquid.

25 A further advantage lies in the provision of an extendible pouring spout, which is inherently formed in one of the ends of the container, such spout being formed from erectable sections of the top end closing panels, as disclosed in my 30 co-pending United States patent application Serial No. 3,246, filed January 24, 1935.

The foregoing and other features of advantage will be apprehended as the herein description 35 proceeds and it will be obvious that modifications may be made in the structure herein without departing from the spirit hereof or the scope of the appended claims.

In the drawings,

Fig. 1 is a view in elevation of the erected, filled 40 and sealed carton, with parts broken away to show the interior details;

Fig. 2 shows the carton in elevation with the pouring spout erected and the carton partly collapsed;

Fig. 3 is a view, similar to Fig. 2, with the carton substantially fully collapsed;

Fig. 4 is a sectional view taken on line 4—4, Fig. 2, looking in the direction of the arrows;

Fig. 5 is a sectional view, taken on the line 5—5, Fig. 1, looking in the direction of the arrows;

Fig. 6 is a plan view of the carton showing the inherent pouring spout, before erection;

Fig. 7 is an enlarged sectional view taken on

the line 7—7, Fig. 3, looking in the direction of arrows;

Fig. 8 is a plan view of Fig. 6 showing the first 5 rupture of the top end closing panels, to develop the pouring spout;

Fig. 9 is a view, similar to Fig. 8, showing the further development of the pouring spout;

Fig. 10 is still a further and final development 10 of the pouring spout, this view being a fragmentary view of Fig. 3, as viewed from the right hand side thereof;

Fig. 11 is a perspective view of the carton liner filled and sealed; and

Fig. 12 is a fragmentary, enlarged transverse 15 sectional view of the sealed upper portion of the liner.

The carton, generally denoted by C, as disclosed, comprises a four sided paper board structure, and a glue lap 7, each side member being provided with an end closing flap on opposite 20 ends, said flaps being glued to one another at said ends to form multiple top and bottom closures of the carton, when filled and sealed.

Two opposite side panels 3 and 6 are provided with traversing score lines 33 and 40, respectively, 25 score line 33 being located near the bottom closure 18, and being parallel thereto, and score line 40 being located near the upper closure end 19, and being parallel thereto. Said score lines 33 and 40 are parallel to each other. Score line 33, 30 Figs. 2 and 3, defines a rectangular sub-side panel 10 on main side panel 3 and score line 40 defines a rectangular sub-side panel 17 from main side panel 6. Score lines 33 and 40, form folding or hinge lines, as seen in Figs. 2 and 3, 35 whereby sub-side panels 10 and 17 may be collapsed flat upon the side panels 3 and 6 respectively, in cooperation with registering score lines located on the adjacent main side panels A and B, which are oppositely located to one another. 40 and will now be described.

The above noted cooperating score lines on main side panel A comprise a central score line 26, Figs. 1 and 2, which runs longitudinally of the mid-section of the side panel A, and terminates short of the bottom and top end closures 18 and 19 and ends at the adjacent bottom and top horizontal score lines 29 and 36 respectively. 45

At the bottom, Fig. 1 are located two diagonal 50 score lines 27 and 28, which commence in each opposite corner of the bottom 18, and, slanting upwardly merge at the joining point of score lines 26 and 29, thus forming a bottom triangular sub-panel 12, and an offset triangular panel 11, as viewed in Figs. 1 and 2.

At the top of the carton, underneath the top closure 18 and commencing at the opposite corners thereof are located two angular score lines 34 and 35, said lines merging into and terminating at the junction of score lines 28 and 36, thus forming a triangular sub-panel 15 and an offset triangular panel 16. Triangular panels 11 and 16 are offset in relatively opposite directions on either side of the mid-score line 28. The opposite side panel B is provided with a set of score lines similar to that described for panel A, the central longitudinal score line 25, indicated in Fig. 5, corresponds to score line 28 on panel A, and the other score lines on panel B correspond to the score lines described for panel A, said other score lines being in registration with the score lines of panel A, so that when it is desired to collapse the carton as indicated in Fig. 3, a slight pressure on side panels 3 and 6 causes the panels 20 A and B to collapse, accordion-like, inwardly, automatically and in orderly folds upon their score lines, from the full erected position of the carton through the stages indicated in Figs. 1, 2 and 3.

As will be observed, in Figs. 2 and 3, the top and bottom end closures 19 and 18, respectively, during the collapsing operation, are drawn inwardly from their normal rectangular positions until their plane surfaces 18-19 are substantially parallel with the collapsed sides 3 and 6. During this movement the top and bottom portions bend on the top and bottom, side or end flap score lines Y and X respectively, Figs. 1, 2 and 3, at opposite corners and ends of the container.

As described, all foldings of the container upon its varied score lines are symmetrical and inward, thus decreasing the volumetric dimensions of the container until, finally all walls and ends are in collapsed flat contact with their adjacent and coacting wall and end members. In this condition the collapsed package is then squeezed sequentially flatwise from the bottom towards the pouring spout P, thus to extract, to a reasonable degree, all of the residual lubricant left therein, such extraction being at a higher degree of speed, than the normal feed flow of the viscous body from the container. Thus time is saved, as the dispensing of the oil is hastened and oil is saved.

The purpose of causing the collapse of the carton on the preformed score lines is to hasten the discharge of the liquid contents therefrom, and is especially useful for emptying the contents quickly, without awaiting for the contents to drain therefrom, as such heavy, or comparatively slow flowing liquids, such as lubricating oils, if being dispensed from the carton directly into the oil compartment of a gas engine, for instance, can be dispensed from the carton very quickly by opening the carton, releasing the oil from the liner, and then progressively collapse the carton longitudinally as described and then, by hand squeezing the carton flat, progressively, from the bottom to the pouring spout end.

As will be noted in Figs. 2 and 3, the carton, when in the act of collapsing has its bottom 18 gradually brought upwardly until it becomes flattened parallel to panel 3, while simultaneously the top portion 19 is gradually brought downwardly until it becomes flattened parallel to the face of the opposite panel 6. As this gradual flattening occurs, the volumetric spaces between the panels 3 and 6, and between the bottom 18 and panel 3 and top 19 and panel 6, become gradually decreased, thus driving the oil forward to

the dispensing spout. When fully collapsed, all of the interior surfaces of the carton come into contact, as illustrated in Fig. 7.

In use as a liquid container, the present container is provided with a flexible liner sack or bag T, Fig. 11, made up of a suitable pliable, oil proof material, which may be cellulosic, formed with an open end, for filling with oil or the like, and being extremely pliable can be of cylindrical contour as shown in Fig. 11, or may 10 be of rectangular contour, and will thus readily conform to the interior of the outer container C when filled with a liquid.

After being filled the open ends of the liner may be over-folded as shown at F in Fig. 12, 15 sealed with an adhesive or heat sealed, if desired, and the filled liner then introduced into an open end of the outer container C, and the container C may then be sealed, and the package is then ready for sale and dispensing.

To dispense the contents, the pouring spout end, Fig. 6, is ruptured on the line of weakness S, the top triangular flaps 23-24 thus formed, are bent backwardly on their respective score lines 23'-24', as illustrated in Fig. 8, and the underlying spout portions 20-21-22 are pulled out on their inner and joint corner score lines 21'-22' and 41-41, Fig. 9, and the adjacent edges of the spout portions 21-22 and 23-24, are pulled apart and upwardly as illustrated in 30 Figs. 2, 3, 4 and 10, thus forming a pointed pouring spout P, with an ovate pouring opening. After the erection of the pouring spout, the inner pliable liner is ruptured or cut, and the liquid contents is then dispensed therefrom, as previously described.

The present structure is economical and after use, is discarded, and its mode of opening to dispense the contents practically renders the device unrefillable. Thus, the package practically 40 guarantees its original contents to the user, when it is opened in the presence of the purchaser.

What is claimed is:

1. A paper board container comprising side panels and end closures, two opposed panels being provided with collapsing portions defined by score lines, two other opposite side panels being provided with oppositely collapsing, hinged sub-panels defined by score lines.

2. A paper board container comprising side panels and end closures, two opposed panels being provided with inwardly collapsing portions defined by traversing, longitudinal and diagonal score lines, two other opposite side panels being provided with hinged oppositely collapsing sub-panels defined by traversing score lines.

3. A paper board container comprising side panels and end closures, two opposed panels being provided with inwardly collapsing portions defined by traversing, longitudinal and diagonal score lines, two opposite side panels being provided with hinged oppositely collapsing sub-panels defined by traversing score lines, the traversing lines on all said panels merging together.

4. A rectangular paper board container comprising four side forming panels and plural wall-ed end closures, two opposed panels being divided into plural, symmetrical sub-panels and adapted to be oppositely and simultaneously collapsed, said collapsible sub-panels being defined by score lines, the other two panels and said end closures being adapted to be also collapsed upon said first sub-panels, the collapsing portions of said second

panels and end closures being defined by score lines.

5. A rectangular paper board container comprising four side forming panels and plural walled end closures, two opposed panels being divided into plural, symmetrical sub-panels and adapted to be oppositely and simultaneously collapsed inwardly, said collapsible sub-panels being defined by score lines, the other two panels and 10 said end closures being adapted to be also oppositely collapsed upon said first sub-panels, the collapsing portions of said second panels and end closures being defined by score lines.

6. A rectangular paper board container comprising four side forming panels and plural walled end closures, two opposed panels being divided into plural, symmetrical sub-panels, said sub-panels being adapted to be simultaneously and oppositely collapsed inwardly towards each 20 other, and being defined by joined score lines, the other two panels being adapted to be also oppositely collapsed upon said first sub-panels, the collapsing portions of said second panels being defined by score lines which merge with the score lines of said first sub-panel score lines.

25. 7. A rectangular paper board container comprising four side forming panels and plural walled end closures therefor, two opposed panels being scored to form sub-panels which coact to

simultaneously fold oppositely and symmetrical-
ly inwardly, the other two panels being scored to cause said end closures to fold inwardly and oppositely upon said first two opposed panels when the container is collapsed.

8. A rectangular paper board container comprising four side forming panels and plural walled end closures therefor, two opposed panels being scored to form sub-panels which coact to simultaneously fold oppositely and symmetrical-
ly inwardly, the other two panels being scored to cause said end closures to fold inwardly simulta-
neously and oppositely with said first sub-panels 10 and to rest upon the opposite sides of said first two opposed panels when the container is col-
lapsed.

9. A rectangular paper board container comprising four side forming panels and plural walled end closures therefor, two opposed panels being scored to form sub-panels which coact to simultaneously and oppositely fold symmetrically 20 inwardly, the other two panels and end closures being scored to cause said end closures to fold oppositely and inwardly upon said first two op-
posed panels when the container is collapsed, one of said end closures being provided an inherent 25 rupturable and erectable pouring spout.

DURYEA BENSEL.
